DISPLAY CARTON

William W. Nowak, Broadview Heights, Ohio, assignor
to Container Corporation of America, Chicago, Ill., a corporation of Delaware

Filed May 9, 1966, Ser. No. 2,235

Term of patent 14 years

(Cl. D58—12)

FIG. 1 is a front perspective view of a display carton showing my new design;

FIG. 2 is a front elevational view thereof, the broken line showing of the toy gun being for illustrative purposes only;

FIG. 3 is a top plan view thereof; and

FIG. 4 is an end elevational view thereof.

I claim:

The ornamental design for a display carton, as shown and described.
